Primary Examiner — Lauren D McVey

(57) **CLAIM**

The ornamental design for a LCD monitor stand as shown and described.

DESCRIPTION

FIG. 1 is a front elevation view of an LCD monitor stand, showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view thereof;

FIG. 8 is another perspective view of the LCD monitor stand closed position; and,

FIG. 9 is another perspective view in another position.

In the drawings, the broken lines illustrate portions of the LCD monitor stand which form no part of the claimed design.

1 Claim, 9 Drawing Sheets
